HYDRAULIC METAL DRAWING PRESS AND
METHOD FOR SHAPING METAL ARTICLES

Walter Ernst, Mount Gilead, Ohio, assignor, by
mesne assignments, to The Hydraulic Press
Corporation, Inc., Wilmington, Del., a corpora-
tion of Delaware

Application January 2, 1929, Serial No. 329,765

22 Claims. (Cl. 113—45)

This invention relates to hydraulic drawing presses and more particularly to drawing presses including male and female dies, one of which is attached to a stationary table fixed to the press frame and the other of which is carried by a platen mounted on the press frame for reciprocatory movements towards and away from the stationary die, and in which press there is provided a hydraulically operated die cushion for clamping 5 the work against the moving die and thus holding the work in proper position relative to the dies during the drawing operation.

When shaping metal into various forms by the drawing process, it is customary to employ a pair 15 of dies consisting of a female die and a male die, one being fixed to a stationary part of a press and the other being carried by the press platen and adapted to move towards and away from the fixed 20 die so that the male die enters the female die and shapes or draws a blank placed on the fixed die to the desired form. When the drawing operation requires what is known as a "deep draw", there is a tendency for the blank to wrinkle. In 25 order to overcome this tendency, various devices known as "blank holders" have been used to yieldingly clamp the blank against the female die. Some of these previously used blank holders have been operated by mechanical means including links and toggles, others by spring loaded 30 devices, and still others by air or hydraulic pressure loaded pistons or rams. The chief disadvantage of all such devices heretofore used is that, each time the nature of the drawing operation is changed, as, for instance, when a heavier 35 or lighter blank is to be drawn, or when a different set of dies is to be used, the blank holder operating means must be adjusted so that the blank holder will clamp the blank under a pressure best suited for the particular drawing operation to be performed.

The main object of the present invention is to provide in a drawing press a die cushion, or blank holder, so arranged that the pressure exerted by the blank holder will always bear a constant ratio to the pressure exerted on the blank by the moving die, so that the blank will automatically be clamped against the female die under only such pressure as is necessary for preventing wrinkling of the blank.

Among other objects of the invention are to provide a press for drawing metal adapted to automatically perform an indeterminate number of drawing operations at a high speed, and to provide such a press in which the speed of the mov-

ing die is automatically reduced as the resistance to drawing increases.

With these and other objects in view, the nature of which will more fully appear, the invention will be understood from the following description, the 5 appended claims, and the several views illustrated in the drawings, in which:

Figure 1 is a front elevation of a hydraulic press, showing some essential operating parts thereof, some parts being shown in section; 10

Figure 2 is an enlarged partial side elevation taken at right angles to Figure 1, with certain parts shown in section;

Figure 3 is a fragmentary vertical sectional view of the lower portion of the press, drawn on 15 an enlarged scale and showing die cushion cylinders in detail;

Figure 4 is a diagrammatic view of the hydraulic circuit, certain of the parts being shown in section; 20

Figure 5 is a longitudinal sectional view of a reversing valve;

Figure 6 is a sectional view taken on the line 6—6 of Figure 5;

Figure 7 is a detail view of a manually oper- 25 able control lever;

Figure 8 is a plan view of a pump cross head;

Figure 9 is a detail view showing the relative 30 positions of a male and a female die and a blank being drawn at an intermediate point in the drawing operation, and;

Figure 10 is a view similar to that shown in Figure 9, the parts being shown in the positions occupied at the end of the drawing operation.

Like numerals designate corresponding parts 35 in the several views illustrated.

Hydraulic presses have been previously built which were capable of automatically performing an indeterminate number of pressing operations; but, due to certain characteristics of the pumps 40 usually employed to furnish the pressure for operating such presses, it has heretofore not been found possible to operate these presses at a high speed, except in the case of small presses where the inertia of the moving parts, and especially 45 that of the pump cross head, is comparatively small.

In connection with such automatic presses it has been usual to employ a variable discharge, 50 reversible pump of the type described in U. S. Letters Patent No. 1,250,170, of December 18, 1917, granted to Hele-Shaw et al. Pumps of this type are provided with a cross-head, the shifting of which reverses the flow of the fluid in

the hydraulic circuit, the reversals producing the reciprocatory motion of the press platen.

While the construction of this type of pump is now well known to those skilled in the art, for the sake of clearness attention is called to the fact that in such pumps there is usually provided a spring adapted to yieldingly hold the pump cross head in a position permitting the pump to deliver its full discharge, there being also provided either mechanical or pressure operated means adapted to move said cross head against the pressure of said spring, thereby progressively reducing the discharge of the pump to zero, and then progressively increasing the discharge of the pump in the opposite direction.

As stated above, when the system is comparatively small, the inertia of the pump cross head is also small, so that it may be quickly shifted to reverse the flow of the fluid under pressure, and a high press operating speed may be thereby attained. It is obvious that, where the press used is large, and the pump cross head correspondingly large, the cross head has an inertia sufficient to oppose the shifting thereof, and to thereby cause a considerable time lag to occur between the strokes of the platen, which naturally is objectionable since it slows down the operating speed of the press.

I have found that, by arranging such a pump to discharge in one direction only, and by providing means whereby the fluid discharged by the pump may be directed alternately to the pressing cylinders and to the push back cylinders operating the press platen, it is possible to attain a high operating speed with a large press.

When operating a large hydraulic press, it is of course essential that the discharge of the pump be reduced as the press platen nears the end of the up and the down strokes, since a sudden reversal of flow of the fluid under pressure when the pump is delivering its full discharge would result in a shock or water hammer in the hydraulic system, such shock being injurious to the various associated parts.

It is to be understood that in the description which is to follow the term "automatic operation" means that kind of operation in which the reciprocatory platen continuously performs an indeterminate number of pressing operations, and the term "semi-automatic operation" means that kind of operation in which the platen performs one complete pressing cycle, and is then brought to rest in its uppermost position.

The invention may be embodied in various types of hydraulic presses, but in the accompanying drawings it is illustrated in connection with a press of the four column downward pressure type. Referring to the drawings, there is shown a hydraulic press A, having a base B, a stationary table C, a press head D connected to said table by four strain rods E, a reciprocatory platen or movable die support F, and a die cushion G. The die support F is guided on the strain rods E in the usual manner. An annular female die H having a lower face *h* and an inner downwardly facing surface *h'* is secured to the under side of the platen, which in effect is a movable support for said die, and in alignment with the female die is a male die or punch I having an upper surface *i*, said punch being bolted to a bolster plate or support J fixedly mounted on the press table and located directly over an opening therein. A circular sheet metal blank K is shown in Figures 1 and 3 as being positioned on the punch

and the die cushion preparatory to being drawn. Figures 9 and 10 respectively illustrate somewhat diagrammatically an intermediate and the final shape assumed by the blank during the drawing operation.

The die cushion G is carried by a supporting plate 1, suspended from lugs 2 or the press frame by means of strain rods 3 threadedly connected at their lower ends to lugs 4 on the supporting plate. A cushioning cylinder 5 is carried by the supporting plate and is preferably positioned directly beneath the punch I, and also carried by the supporting plate on opposite sides of the cushioning cylinder are blank holder returning cylinders 6-6, equally spaced from the cushioning cylinder and preferably of somewhat lesser diameter than the latter. Mounted for reciprocation in the cylinder 5 is a cushioning plunger or ram 7, and in the cylinders 6-6 blank holder returning rams 8-8 are mounted. The rams 7 and 8-8 are connected at their upper ends to a yoke 9. Connected to the yoke by means of pins 10 extending through openings 11 in the die support or bolster plate is a blank holder or clamping ring 12 concentrically arranged around the punch I. This clamping ring is preferably of substantially the same inside and outside diameters as the female die H and it will be apparent that, when the latter descends and passes over the punch, the blank K which is positioned on the clamping ring will be clamped between the latter and the lower face of the female die. A plurality of vertically disposed guide standards 13-13 bolted to the bolster plate and arranged circumferentially around the clamping ring guides the said ring during its reciprocatory movements, thus relieving the pins 10 of any lateral thrust to which said pins might otherwise be subjected.

A variable discharge pump 14 of the type above referred to is connected to a surge tank 15 by means of a suction pipe 16, as shown in Figure 4. The discharge of the pump is directed through a pipe line 17 which is connected to a reversing valve 18. The valve 18 also has connected to it a pipe line 19, which leads to booster cylinders 20 and to one side of a surge shifting valve 21, located in the surge tank 15, a pipe line 22 which leads to push back or die returning cylinders 23 and to the other side of the surge shifting valve 21, and a pipe line 24 which leads to and opens into the surge tank 15. The surge shifting valve 21 is preferably mounted directly on top of a main pressing cylinder 25 and is arranged to communicate therewith by means of a port 25a. As will be hereinafter described, the reversing valve 18 is adapted to direct fluid under pressure alternately to the pressing cylinder 25 and to the die returning cylinder 23 to effect reciprocations of the movable die support F, the two cylinders thus constituting hydraulic actuating means for reciprocating the movable support.

The cushioning cylinder 5 communicates with the main pressure cylinder 25 by means of a pipe line 26, and, since there are no valves in this pipe line, the cushioning cylinder and the pressing cylinder are always in direct communication, and it is therefore apparent that the unit pressure in the cushioning cylinder will always be the same as that in the pressing cylinder. The cushioning ram 7 is of smaller diameter than the main pressing ram 27 so that the total pressure exerted upwardly on the cushioning ram will be at all times less than the pressure exerted upon the pressing ram, and as a result the clamping ring will be

forced downwardly by the female die when the die descends. Because of the constant open communication between the cushioning cylinder 5 and the main pressing cylinder 25, the total effective pressure exerted on the cushioning ram 8 will always bear a constant ratio to the total effective pressure exerted on the main pressing ram 21. In other words, when the drawing pressure is large and results in a marked tendency for the blank to wrinkle, the pressure exerted upon the blank by the clamping ring will also be large, and wrinkling of the blank will be effectively prevented. When the drawing pressure is relatively small, the clamping pressure will also be relatively small and the blank will not be unnecessarily squeezed.

The construction and the operation of the reversing valve 18 will be hereinafter described in detail, but for the sake of clearness it will, for the present, be sufficient to say that the valve is adapted to be set in either of two positions, in the first of which positions the pipe line 17 is placed in communication with the pipe line 19, and the pipe line 22 with the pipe line 24, and in the second of which positions the pipe line 17 is placed in communication with the pipe line 22, and the pipe line 19 with the pipe line 24.

The surge shifting valve 21 is provided with a valve casing 29 having a valve chamber 30 which communicates with the surge tank 15 by means of a port 31, and with the main cylinder 25 of the press by means of the port 25a. Slidably mounted in the chamber 30 is a balanced piston valve 32, said valve being provided at one of its ends with a tail rod 33, the tail rod being slidable in a bore 34. The bore 34 communicates with the chamber 30 by means of the passage 35, and also with the pipe line 19. The valve 32 is also provided with a second tail rod 36 which extends through a chamber 37 into a bore 38 in a casing 39 attached to the casing 29, and into a chamber 40 in said casing 39, the chamber 40 communicating at its outer end with the pipe line 22. It may be noted that, when the piston valve 32 is in the position shown in the drawing, the main cylinder 25 communicates with the surge tank 15 by means of the port 25a, the chamber 30 and the port 31, but, when the piston valve is caused to be shifted to the left in a manner to be hereinafter described, the cylinder 25 will communicate with the pipe line 19 by means of the port 25a, the chamber 30, the passage 35, and the bore 34.

Mounted on the top of the valve casing 29 and adapted to communicate with the chamber 37 is a check valve 40, which comprises a casing 41, ports 42, 42, and 43, and a valve ball 44 which is urged to closed position by a spring 45, the tension of which spring may be adjusted by means of a threaded plug 46 for a purpose hereinafter specified. It is to be noted that, when the piston valve 32 is moved to the left in the plane of the drawings, fluid contained in the chamber 37 will be expelled through the check valve 40 into the surge tank 15, but that no fluid will enter the chamber 37 through said check valve.

Mounted on the bottom of the casing is a second check valve 47 adapted to communicate with the chamber 37 by means of the port 48 and with the surge tank 15 by means of the port 49. It is to be noted that, though no fluid will be discharged from the chamber 37 through the valve 47 and into the surge tank 15, the valve ball 50 is kept seated by gravity, and by the pressure in the chamber 37, so that when the piston valve 32

moves to the right in the plane of the drawing the ball 50 will be lifted from its seat by the suction created in the chamber 37, thus allowing fluid to flow from the surge tank 15 through the ports 49 and 48 into the chamber 37.

With more particular reference to the reversing valve 18, there is shown in Figures 5 and 6 a valve casing 51 having a central chamber 52 and a piston valve 53 slidably longitudinally in the bore forming said chamber, and being closely fitted therein. In order to facilitate the connecting of the control valve 18 to the pipe lines 19 and 22, there are provided detachable plates 54 which are bolted or otherwise attached to the valve casing 51, tongue and groove connections 55 forming pressure tight joints between the plates 54 and the valve casing 51. The plates 54 are provided with threaded bores which receive the ends of the pipes 19 and 22, thereby placing said pipes in communication with the valve chamber 52 by means of ports 56 and 57 respectively. The pipe line 17 communicates with the valve chamber 37 by means of a port 58, and it is to be noted that when the piston valve 53 is in the position shown in Figures 5 and 6 the pipe line 17 communicates with the pipe line 19 by means of the port 58, the valve chamber 52, and the port 56. When the piston valve is moved to the right in the plane of the drawing in a manner to be hereinafter described, the pipe line 17 will be placed in communication with the pipe line 22 by means of the port 58, the valve chamber 52, and the port 57. In one end of the valve casing 51 is a bore 59 into which is closely fitted a ring 60 provided with spaced abutment ribs 61, which ribs project into one end of a passage 62 and serve to limit the travel of the piston valve 53 in that direction. The ring 60 is provided with a flange 63 which fits into a suitable counter sunk portion of the bore 59, said ring being held firmly in place by a clamping plate 64. The clamping plate 64 is provided with a threaded bore which receives the pipe 24, thus placing said pipe in communication with the valve chamber 52 by means of a port 65 which extends through the plate 64 and the ring 60, and the passage 62. With the piston valve 53 in the position shown in Figures 5 and 6, the pipe line 24 communicates with the pipe line 22 by means of the port 65, the passage 62, the valve chamber 52, and the port 57. When the piston valve 53 is moved to the right from the position shown in the drawings, the pipe line 24 is placed in communication with the pipe line 19 by means of the port 65, the valve chamber 52, and the port 56.

At one end of the piston valve 53 there is provided a rod 66 extending through the valve chamber 52 and beyond the valve casing 51, the rod 66 sliding in a bore 67 provided with a suitable packing gland 68. At the outer end of the rod 66 there is provided a collar 69 rigidly attached to said rod by a pin or other suitable attaching means.

The valve casing 51 is provided with chambers 70, 70 communicating with pipe lines 71, 71 by means of ports 72, 72. The pipe lines 71, 71 communicate at all times with the pipe line 19 so that the same fluid pressure is caused to exist in the chambers 70, 70 as in the pipe line 19.

Adapted to slide in packing glands 73 in the valve casing 51, and projecting into the chambers 70, 70, are plungers 74, 74, said plungers sliding in bearings 75 in a bracket 76 bolted to a flange 77 on the valve casing 51. A cross bar 78

- is attached to the plungers 74, 74 by means of nuts 79, 79.
- Slidably mounted on the plungers 74 and the rod 66 is a cross head 80 equipped with suitable bushings 81. The plungers 74 are provided with collars 82 adapted to abut the cross head 80 and to thereby move said cross head to the right in the plane of the drawing when said plungers are caused to be moved to the right.
- 10 A spring loaded compressible link 83 is loosely pivoted at one end to the cross head 80 and at its other end to a pin 84 on the bracket 76, while a second and similar link 85 is loosely pivoted at one end to the cross head 80 and at the other end is fixed to a rock shaft 86 journaled in the bracket 76. It is to be noted that the links 83 and 85, and the cross head 80, which in effect is also a link, comprise a spring loaded toggle, so that when the plungers 74 move to the right, 20 forcing the cross head 80 ahead of them, the center of the cross head 80 will eventually reach a point just to the right of a line connecting the centers of the pivot pin 84 and the rock shaft 86, at which time the toggle will quickly snap to its 25 extreme position, whereby the cross head 80 will strike the collar 69 on the rod 66 and move said rod and the piston valve 53 to the right. By rocking the shaft 86 in a counterclockwise direction by means hereinafter described, the toggle will be caused to move in the opposite direction, finally snapping to the left and causing the cross head 80 to abut a shoulder 87 on the rod 66, thereby shifting the piston valve 53 to the left.
- 30 35 Mounted in a boss 88 on the bracket 76 and extending longitudinally of the rod 66 is a stem 89 provided at its inner end with a shoulder 90 abutting a shoulder 91 in the boss 88, a clamping nut 92 being threaded to the stem 89 and 40 serving to hold the shoulder 90 against the shoulder 91, thereby locking the stem 89 to the boss 88. A set screw 93 in the boss 88 prevents the stem 89 from turning relative to said boss. In 45 the inner end of the stem 89 there is provided a recess 94 permitting the rod 66 and the collar 69 to move to the right, the bottom of said recess limiting the movement of said rod and nut in that direction.
- 50 Slidably mounted on a reduced portion 85 of the stem 89 is a collar 96 which is urged against a shoulder 97 on said stem by means of a coil spring 98. A hand wheel 99 is threaded on the outer end of the stem 89 and is adapted to vary the expansive force of said spring. A spring 55 seat 100 and a thrust bearing 101 are interposed between the hand wheel and the spring to facilitate the turning of said hand wheel, and a nut 102 prevents the hand wheel from being accidentally removed from the stem 89.
- 60 Referring to Figure 1, there is shown a vertically disposed operating rod 103, slidably mounted in lugs 104 and 105 on the stationary table C and the press head D respectively, the downward movement of said rod being limited by a collar 106 adjustably fixed to the rod. The operating rod 103 is constantly urged to its lowermost position by gravity and also by means of a coil spring 107 mounted on said rod between the lug 105 and a collar 108 also on said rod. A boss 109 on the movable die support is arranged to slide freely on the operating rod 103. Adjustably attached to the rod 103 is a collar 110 which is adapted to be engaged by the boss 109 when the 70 movable support has reached a predetermined point in its upward travel, the rod 103 being thereby lifted.
- 75 80 Located above the collar 110 is a rocker arm 113 having an arcuate projection 114 adapted to be engaged by the collar 110, said rocker arm having one of its ends fixed to the shaft 86 and its other end pivoted to a coupling link 115. Rigidly attached to the coupling link 115 is a rod 116 adapted to slide in a hollow coupling 117, the latter being pivotally connected at 118 to a manually operable control lever 119. A tensioned coil spring 120 interposed between the press base B and the shorter arm of the bell crank lever tends to cause a lug 121 on 15 said handle to abut a lug 122 on the base B, thereby normally maintaining the bell crank lever in the position shown in the drawing.
- 85 90 As clearly shown in Figure 7, there is rigidly attached to the upper end of the rod 116 a collar 123 which is adapted to slide within the hollow coupling 117 and to abut the inwardly extending flange 124, thereby limiting the downward movement of the rod 116 relative to the coupling 117. It is apparent that, although the 95 control lever 119 may be swung to the left and the rod 116 thereby elevated, an upward movement of the rod 116 will not cause the control lever to be moved. Thus, when the rod 116 is caused to perform a reciprocatory motion during constant operation of the press in a manner hereinafter described, there will be no danger of the control lever swinging outwardly and striking the operator.
- 100 105 In Figures 1, 2, and 8 there is shown a mechanism for controlling the rate of discharge of the pump. This mechanism is provided with a vertically disposed and longitudinally adjustable operating rod 125 slidably mounted in lugs 126 and 127 on the stationary table C and the press head D respectively. The downward movement of said rod is limited by collars 128 and 129 fixedly attached to the rod. The operating rod 125 is constantly urged to its lowermost position by gravity and by means of a coil spring 130 mounted on 110 said rod and interposed between the lug 127 and a collar 131 on the rod. A boss 132 on the movable support is arranged to slide freely on the operating rod 125. Adjustably attached to the rod 125 is a collar 133 which is adapted to be 115 engaged by the boss 132 when the movable support has reached a predetermined point in its upward travel, the rod 125 being thereby lifted.
- 120 125 Rigidly attached to the base B directly below the lug 126 is a bracket 134 to which a bell crank lever 135 is pivoted as at 136. A link 137 is pivoted to the operating rod 125 at 138 and to the bell crank lever 135 at 139. A link 140 disposed at right angles to the operating rod 125 is pivotally connected to the bell 130 crank lever at 141. A lever 142, pivotally mounted at 143 on a bracket 144 carried by the pump, has one of its ends pivotally connected at 145 to the link 140. The other end of the lever 142 is provided with a rounded head 146 which is 135 engaged by a cross head 147 on the pump 14, whereby a clockwise movement of the lever 142 will cause the pump cross head to be pushed towards the center of the pump, thus decreasing the discharge of the pump in a manner well 140 known to those skilled in the art. As stated above, pumps of this type are provided with a spring for returning the cross head to a position permitting full discharge of the pump when the externally applied force, such as the pressure 145

exerted on the cross head by the lever 142, is removed.

Operation

If it is desired that the press operate under full automatic control, the collar 110 is adjusted in a position on the operating rod permitting said collar to be engaged by the boss 109 at the proper point in the up stroke of the movable support, and the motor driving the pump then started.

Assuming that this adjustment of the collar 110 has been made, that the motor driving the pump has been started, and that the movable support F is travelling downward, the various parts comprising the automatic control mechanism will be in the positions shown in the drawings, the blank K will have been placed on the punch as shown in Figure 1, and the operation of the press will be as follows:

The pump 14 is set to deliver its full discharge of fluid under pressure through the pipe line 17 into the reversing valve 18, the fluid then passing through the port 58, the valve chamber 52, the port 56, and the pipe line 19 and into the booster cylinders 20, the fluid pressure thereby exerted in said booster cylinders causing the movable support to move downwardly. During this part of the down stroke of the support, fluid from the surge tank 15 will flow through the port 31, the valve chamber 30, and the port 25a into the main cylinder 25. It is to be noted that, during the down stroke of the support, the fluid which entered the die returning cylinders 23 and the return cylinders 6, 6 during the preceding up stroke must escape from said cylinders, the fluid escaping from the die returning cylinders by means of the pipe line 22, the port 57, the valve chamber 52, the passage 62, the port 65, and the pipe line 24, which pipe line discharges said fluid into the surge tank 15, and the fluid in the return cylinders escaping through the pipe line 28 into the die returning cylinders and thence over the same path as the fluid which was in the die returning cylinder.

When the female die H contacts the blank K, further movement of the platen and the die will be resisted, firstly, by the resistance to bending of the blank which is supported on the fixed punch I, and, secondly, by the clamping ring 12 contacting the blank K, the clamping ring being yieldably urged upwardly by pressure in the cushioning cylinder 5. When the female die first engages the blank, the pressure in the cushioning cylinder 5 is small, being due only to the static head of the fluid in the surge tank 15. It is to be noted that, in the interval during which the female die is moving from its uppermost position to its point of contact with the blank, the full discharge of the pump is directed to the booster cylinders, which are of relatively small diameter. This results in a rapid die travel during the inactive portion of the down or drawing stroke, so that a minimum of time is consumed in bringing the dies into actual drawing relation.

As the drawing of the blank starts, the female die and its movable support will encounter resistance to their downward travel, and the fluid pressure in the pipe lines 17 and 19 will build up until it reaches a predetermined value, at which time said pressure, acting on the tail rod 33 of the surge shifting valve 21, will cause the piston valve 32 to be moved to the left from the position shown in the drawing, thereby expelling the fluid contained in the chamber 37 through

the ports 43 and 42 of the check valve 40. It is to be noted that, by varying the pressure exerted on the ball 44 by the spring 45, the fluid pressure in the pipe line 19 necessary to move the piston valve to the left may be varied at will.

After the piston valve 32 has been moved to the left as described above, the valve chamber 30 will be shut off from communication with the port 31 by the righthand end portion of said valve, and, at the same time, said valve chamber 30 will be placed in communication with the pipe line 19 by means of the passage 35 and the bore 34, which bore has been vacated by the tail rod 33. The main cylinder 25 now receives the fluid under pressure from the valve chamber 30 through the port 25a. The movable support, now being forced downwardly by the combined action of the main and booster cylinders, continues said downward movement until the resistance to drawing causes the pressure to build up in the circuit and then to act to move the pump cross head inwardly against the pressure of the cross head spring, thus decreasing the rate of discharge from said pump and preventing the occurrence of shocks of water hammer which might otherwise take place when the flow of fluid under pressure is reversed to start the support on its upward movement. During the drawing of the blank, the building up of the pressure in the main pressing cylinder 25 has resulted in a proportional increase in pressure in the cushioning cylinder 5, the blank being thereby clamped between the clamping ring 12 and the female die by a force proportional to the drawing pressure, that is the ratio of the blank holding pressure to the drawing pressure is constant for all values of drawing pressure, and wrinkling of the blank is thereby prevented.

When the drawing operation has been completed and the female die has reached the position shown in Figure 10, the blank (now drawn) will be subjected to a finishing, or pressing, operation. The formed blank will be tightly pressed between the top surface i of the punch and the inner downwardly-facing surface h' of the female die, a very smooth finished article, free from wrinkles or other imperfections sometimes caused by drawing, being thereby produced. This pressing of the blank between the two dies results in a building up of the pressure in the main cylinder, and the movable support will be reversed and returned to its upper or normal position as follows:

As has been heretofore stated, the chambers 70 are always in communication with the pipe line 19 by means of the ports 72 and the pipe line 71, so that, as the fluid pressure builds up in the main and booster cylinders, the pressure will increase correspondingly in said chambers, until a predetermined pressure has been reached, at which time the plungers 74 will be forced to the right. This movement of the plungers 74 will cause the cross bar 78 to slide on the stem 89, and the collars 82 to abut the cross head 80 and thereby move said cross head to the right against the force exerted by the spring loaded compressible links 83 and 85. When the vertical center line of the cross head 80 has reached a point just a little to the left of a plane containing the centers of the pin 84 and the rock shaft 86, the cross bar 78 will abut the collar 96, the plungers 74 being thereby held against further movement to the right until the fluid pressure in the chambers 70 has further built up. When

said pressure has further built up to a predetermined value, the force exerted by the plungers 74 and the cross bar 88 on the collar 96 will cause said collar to slide to the right against the pressure of the spring 98, thus allowing the plungers 74 to move further to the right, until the cross head 80 has passed the plane containing the pin 74 and the rock shaft 86, at which time the spring loaded compressible links 83 and 85 10 will cause the toggle to snap quickly to the right, the cross head 80 striking the collar 69 on the rod 66, moving said rod and the piston valve 53 to the right.

From the foregoing it is apparent that the travel 15 of the platen and the female die is reversed upon the attainment of a definite pressure in the main pressing cylinder 25, and that the reversal is not directly dependent upon any distance control means. This characteristic will at once be seen 20 as an important advantage when it is remembered that dies of any depth, within reasonable limits, may be placed on the machine and operated in the above manner without the necessity of making new adjustments for each different set of dies 25 in order to properly control the length of stroke of the movable die.

It is to be noted that, by turning the hand wheel 99 and thus varying the tension of the spring 98, the amount of pressure which must build up 30 in the main and booster cylinders before the valve 18 is reversed may be varied at will.

As has been described above, when the piston valve 53 has been moved to the right, the pipe line 17 will communicate with the pipe line 22, 35 and the pipe line 19 with the pipe line 24. In this position of the valve, the discharge of the pump is directed through the pipe lines 17 and 22 into the die returning cylinders 23 and the chamber 40 in the surge shifting valve 21. The fluid 40 pressure in the chamber 40 acts on the tail rod 36 causing the piston valve 32 to be moved to the right, in other words, to the position shown in Figure 4. While the piston valve is moving to the right, fluid from the surge tank 15 will enter the 45 chamber 37 through the check valve 41 as hereinbefore described. The fluid under pressure in the die returning cylinders 23 then causes the movable support to move upwards, the fluid contained in the main cylinder 25 then being expelled therefrom into the surge tank 15 through the port 25a, the valve chamber 30, and the port 31, and the fluid in the booster cylinders 20 being expelled through the pipe line 19, the reversing valve 18, and the pipe line 24 into the 50 surge tank 15.

Since the blank holder returning cylinders 6 are in constant communication with the die returning cylinders by means of the pipe line 28, fluid will enter the return cylinders 23 during the 60 upward movement of the platen, and will move the rams 8-8 upwardly to return the clamping ring 12 to its upper position. The upward movement of the rams 8-8 is limited by the yoke 9 contacting with the bolster plate J, and the pins 65 10 are of such a length that, when the return rams have reached their upper limit, the upper face of the clamping ring will lie in substantially the same plane as the upper face of the punch.

70 It is to be noted that, since the pressure in the pipe line 17 is less at this time than it was at the time the movable support met resistance to its downward travel, the spring on the pump cross head will return said cross head to the position 75 permitting maximum discharge by the

pump, thereby causing the movable support to be rapidly returned to its uppermost position.

When the support reaches a predetermined point on its upward travel the boss 132 carried by said support will strike the collar 133 on the operating rod 125, thereby lifting said rod and causing the lever 142 to be swung in a clockwise direction by means of the link 137, the bell crank lever 135, and the link 140. By this movement of the lever 142, the head 146 of said lever forces the cross head 147 of the pump inwardly against the force of the pump cross head spring, thereby reducing the rate of discharge from the pump preparatory to a reversal of direction of travel of the movable support for the purpose stated above. 15

When the support has proceeded a little farther on its upward travel, and has reached a predetermined point, the boss 109 will strike the collar 110 on the operating rod 103, lifting said operating rod, whereby the collar 111 contacts with the 20 arcuate projection 114 on the rocker arm 113, causing said rocker arm to be swung upwardly, thus turning the rock shaft 86 in a clockwise direction as viewed in Figure 1 and in a counterclockwise direction as viewed in Figure 6. This 25 turning of the shaft 86 causes the compressible link 85 which is fixed to the rock shaft to be swung to the left, whereby the cross head 80 will be also swung to the left, during which movement the cross head will strike the collars 82 30 on the plungers 74, and the shoulder 87 on the rod 66, thereby returning the plungers to their inner position and the piston valve 53 to the position shown in Figures 5 and 6. In this position of the piston valve 53, the pipe line 17 communicates with the pipe line 19, whereby the platen will start another downward stroke. The movable support will in this way continue to reciprocate until the motor driving the pump is shut off, whereupon the press will, of course, 35 cease operating.

If it is desired to operate the press semi-automatically, or, in other words, in such a way that the dies will perform one drawing operation and the female die then return to its uppermost position and stop, the collar 110 on the operating rod 103 is loosened and moved up into a position in which it will not be engaged by the boss 109. Assuming that the movable support is on its downward stroke, the completion of said downward stroke and the start of the upward stroke will be executed in the same manner as that described above. When the boss 132 strikes the collar 133 on the upward stroke of the support, the rod 125 will be lifted and the pump cross head 147 moved inwardly in the manner already described, until said cross head has reached a point at which the discharge of the pump is zero, the movable support then coming to rest. 55

To cause the movable support to descend to cause the dies to perform another drawing operation, the manually operable control lever 119 is swung to the left from the position shown in Figure 1, thereby raising the rod 116, swinging the lever 113 upwardly, and turning the rock shaft 86 in a clockwise direction as viewed in Figure 1 and in a counterclockwise direction as viewed in Figure 6. The piston valve 53 is thereby moved to the left in the manner described above, and the pipe line 17 will then communicate with the pipe line 19, and the pipe line 22 with the pipe line 24. It may be noted that, though the valves 18 and 21 are now in a position to allow fluid under pressure to produce a downward movement of the platen, the 70 75 80 85 90 95

pump is at this time delivering no fluid under pressure to produce such a downward stroke. However, since the main cylinder 25 communicates with the surge tank 15 by means of the 5 port 25a, the chamber 30, and the port 31, the die returning cylinders 23 with the surge tank by means of the pipe line 22, the valve 18, and the pipe line 24, and the booster cylinders 20 with the surge tank by means of the pipe line 10 19, the valve 18, the pipe line 17, the pump 14, and the pipe line 16, there is no fluid pressure tending to hold the movable support up. The weight of the support itself will therefore cause the latter to coast downwardly until the operating rod 125 has been lowered and the pump cross head 147 thereby allowed to be moved outwardly by the cross head spring, whereupon the pump will start to discharge and the operation will proceed in the manner already described.

20 While one method of carrying out my invention has been herein described, it is of course to be understood that the details of structure and arrangements of parts may be variously changed and modified without departing from the spirit 25 and scope of my invention.

I claim:

1. In a drawing press including a movable die and a movable blank holder; the combination with hydraulic actuating means for moving said 30 die towards said holder; of a source of fluid pressure connected to said means; hydraulic cushioning means associated with said blank holder for yieldably urging said blank holder towards said die; and hydraulic connections between said actuating means and said cushioning means for maintaining at a constant ratio the hydraulic pressures therein.

2. In a drawing press including a reciprocating die and a movable blank holder, the combination with hydraulic actuating means for reciprocating said die towards and away from said holder; of a source of fluid pressure connected to said actuating means; hydraulic cushioning means associated with said blank holder for yieldingly urging said blank holder towards said die during movement of the die towards said holder, and for moving the blank holder towards the die while the die is moving away from said holder, and hydraulic connections between said 45 hydraulically actuated die moving means and said hydraulic cushioning means for maintaining at a constant ratio the hydraulic pressures therein.

3. In a drawing press, including a press frame, 55 the combination with a pair of die supports mounted on the frame, one of said supports being movable towards and away from the other; of hydraulic actuating means for effecting alternate drawing and return strokes of said movable support, said actuating means including a main pressing cylinder; a die fixed to each support; a source of fluid pressure; means forming with the pressing cylinder and with said source of fluid pressure a hydraulic circuit; a blank holder adapted to clamp a blank against one of the dies; a cushioning cylinder; hydraulically actuated means mounted for reciprocation in said cushioning cylinder and connected to said blank holder for resisting movement of said 60 holder during the drawing stroke; hydraulic connections between the pressing cylinder and the cushioning cylinder for maintaining proportionate pressures therein; and circuit controlling means operatively connected with the circuit for causing said hydraulically actuated means to effect alternate drawing and return strokes of the movable support.

70

effect alternate drawing and return strokes of the movable support.

4. In a drawing press, including a press frame, the combination with a pair of die supports mounted on the frame, one of said supports being 5 movable towards and away from the other; of hydraulic actuating means for effecting alternate drawing and return strokes of said movable support, said actuating means including a main pressing cylinder; a die fixed to each support; a source of fluid pressure; means forming with the pressing cylinder and with said source of fluid pressure a hydraulic circuit; a blank holder normally occupying a position at rest and being adapted to clamp a blank against one of the dies, 10 said holder being also adapted to be moved away from its normal position by the die during the drawing stroke of the latter; a cushioning cylinder; hydraulically actuated means mounted for reciprocation in said cushioning cylinder and 15 connected to said blank holder for resisting movement of said holder during the drawing stroke; hydraulic connections between the pressing cylinder and the cushioning cylinder for maintaining proportionate pressures therein; 20 hydraulically actuated means associated with the blank holder and connected to said hydraulic circuit for returning said holder to its normal position during the return stroke of the movable support; and circuit controlling means operatively connected with the circuit for causing said 25 hydraulically actuated means to effect alternate drawing and return strokes of the movable support.

5. In a drawing press, including a press frame, the combination with a pair of die supports mounted on the frame, one of said supports being movable towards and away from the other; of hydraulic actuating means for effecting alternate drawing and return strokes of said movable support; said actuating means including a main pressing cylinder, and a die returning cylinder; a die fixed to each support; a source of fluid pressure; means forming with the pressing cylinder and with said source of fluid pressure a hydraulic circuit; a blank holder normally occupying a position at rest and being adapted to clamp a blank against one of the dies; a cushioning cylinder; hydraulically actuated means mounted for reciprocation in said cushioning cylinder and 35 connected to said blank holder for resisting movement of said holder during the drawing stroke; hydraulic connections between the pressing cylinder and the cushioning cylinder for maintaining proportionate pressures therein; a blank holder returning cylinder; hydraulically actuated means mounted for reciprocation in said blank holder returning cylinder and connected to the blank holder for returning the latter to its 40 normal position during the return stroke of the movable support; hydraulic connections between the die returning cylinder and the blank holder returning cylinder; and circuit controlling means operatively connected with the circuit for causing said 45 hydraulically actuated means to effect alternate drawing and return strokes of the movable support.

6. In a drawing press including a press frame, the combination with a bolster plate connected to the frame and having an opening; of a die connected to the upper face of the bolster plate; a movable die support mounted on the frame for performing drawing and return strokes respectively towards and away from said die; a second die mounted on said support; hydraulic actuating 50

means for effecting reciprocatory movements of said support, said actuating means including a main pressing cylinder; a source of fluid pressure; means forming with the pressing cylinder and with said source of fluid pressure a hydraulic circuit; a cushioning cylinder connected to said frame below the bolster plate; cushioning means mounted in said cushioning cylinder for reciprocatory movements; a blank holder adapted to 5 clamp a blank against the moving die, said blank holder being arranged in cooperative relation with the die on the bolster plate; means extending through the opening and connected to said reciprocatory cushioning means and to the blank 10 holder for resisting movement of said holder during the drawing stroke; hydraulic connections between the pressing cylinder and the cushioning cylinder for maintaining proportionate pressures therein; and circuit controlling means for causing 15 said hydraulic actuating means to effect drawing and return strokes of the movable support.

7. In a drawing press including a press frame, the combination with a bolster plate connected to 20 the frame and having openings; of a die connected to the upper face of the bolster plate; a movable die support mounted on the frame for performing drawing and return strokes respectively towards and away from said die; a second 25 die mounted on said support; hydraulic actuating means for effecting reciprocatory movements of said support, said actuating means including a main pressing cylinder and a die returning cylinder; a source of fluid pressure; means forming 30 with the pressing cylinder and with said source of fluid pressure a hydraulic circuit; a cushioning cylinder connected to said frame below the bolster plate; a cushioning ram mounted in said cushioning cylinder for reciprocatory movements; a blank holder returning cylinder connected to the frame and disposed adjacent the cushioning cylinder; a ram mounted for reciprocatory movements in said returning cylinder; a blank holder for clamping a blank against the 35 moving die and arranged in cooperative relation with the die on the bolster plate; means extending through the openings in the bolster plate and connecting said blank holder to the blank holder returning ram and to the cushioning ram; hydraulic 40 connections between the pressing cylinder and the cushioning cylinder for maintaining proportionate pressures therein to urge the blank holder against the moving die; hydraulic connections between the die returning cylinder and the blank holder returning cylinder; and circuit controlling means for causing 45 said hydraulic actuating means to effect drawing and return strokes of the movable die.

8. In a drawing press including a press frame, 50 the combination with a bolster plate connected to the frame and having openings; of a die connected to the upper face of the bolster plate; a movable die support mounted on the frame for performing drawing and return strokes respectively toward and away from said die; a second die mounted on said support; hydraulic actuating means for effecting reciprocatory movements of said support, said actuating means including a main pressing cylinder and a die returning cylinder; a source of fluid pressure; means forming 55 with the pressing cylinder and with said source of fluid pressure a hydraulic circuit; a cushioning cylinder connected to said frame below the bolster plate; a cushioning ram mounted in said

cushioning cylinder for reciprocatory movements; a blank holder returning cylinder connected to the frame and disposed adjacent the cushioning cylinder; a ram mounted for reciprocatory movements in said returning cylinder; a blank holder for clamping a blank against the moving die and arranged in cooperative relation with the die on the bolster plate; a yoke connected to said cushioning ram and to said blank holder returning ram, said yoke being arranged 10 in substantial parallelism with the bolster plate, and being adapted to engage said plate to limit the movement of said rams in one direction; means extending through the openings in the bolster plate and connecting the blank holder to 15 said yoke; hydraulic connections between the pressing cylinder and the cushioning cylinder for maintaining proportionate pressures therein to urge the blank holder against the moving die; hydraulic connections between the die returning 20 cylinder and the blank holder returning cylinder; and circuit controlling means for causing said hydraulic actuating means to effect drawing and return strokes of the movable die.

9. In a drawing press, including a press frame, 25 the combination with a pair of die supports mounted on the frame, one of said supports being movable towards and away from the other; of hydraulic actuating means for effecting alternate drawing and return strokes of said movable 30 support, said actuating means including a main pressing cylinder; a die fixed to each support; a source of fluid pressure; means forming with the pressing cylinder and with said source of fluid pressure a hydraulic circuit; a blank holder 35 adapted to clamp a blank against one of the dies; a cushioning cylinder; hydraulically actuated means mounted for reciprocation in said cushioning cylinder and connected to said blank holder for resisting movement of said holder during 40 the drawing stroke; hydraulic connections between the pressing cylinder and the cushioning cylinder for maintaining proportionate pressures therein; circuit controlling means operatively 45 connected with the circuit for reversing the direction of fluid travel to reciprocate the movable support; and means responsive to the fluid pressure in the circuit for decreasing the speed 50 of travel of the movable support when said support approaches the limit of its drawing stroke.

10. In a drawing press, including a press frame, the combination with a pair of die supports mounted on the frame, one of said supports being movable towards and away from the other; of hydraulic actuating means for effecting alternate 55 drawing and return strokes of said movable support, said actuating means including a main pressing cylinder; a die fixed to each support; a source of fluid pressure; means forming with the pressing cylinder and with said source of fluid pressure a hydraulic circuit; a blank holder adapted to clamp a blank against one of the dies; a cushioning cylinder; hydraulically actuated 60 means mounted for reciprocation in said cushioning cylinder and connected to said blank holder for resisting movement of said holder during the drawing stroke; hydraulic connections between the pressing cylinder and the cushioning cylinder for maintaining proportionate pressures 65 therein; means operatively connected in the circuit and responsive to the fluid pressure therein for reversing the direction of fluid travel upon the building up in the circuit of a predetermined pressure; and means actuated by the movable 70

- support and operable at the end of the return stroke for reversing the direction of fluid travel.
11. In a drawing press, including a press frame, the combination with a pair of die supports mounted on the frame; one of said supports being movable towards and away from the other; of hydraulic actuating means for effecting alternate drawing and return strokes of said movable support, said actuating means including a main 5 pressing cylinder; a die fixed to each support; a source of fluid pressure; means forming with the pressing cylinder and with said source of fluid pressure a hydraulic circuit; a blank holder adapted to clamp a blank against one of the dies; a cushioning cylinder; hydraulically actuated means mounted for reciprocation in said cushioning cylinder and connected to said blank holder for resisting movement of said holder during the drawing stroke; hydraulic connections between the pressing cylinder and the cushioning cylinder for maintaining proportionate pressures therein; means operatively connected in the circuit and responsive to the fluid pressure therein for reversing the direction of fluid travel when the drawing stroke has been completed; and means actuated by the movable support and operable at the end of the return stroke for reversing the direction of fluid travel.
12. In a drawing press, including a press frame, the combination with a pair of die supports mounted on the frame, one of said supports being movable towards and away from the other; of hydraulic actuating means for effecting alternate drawing and return strokes of said movable support, said actuating means including a main pressing cylinder; a die fixed to each support; a source of fluid pressure; means forming with the pressing cylinder and with said source of fluid pressure a hydraulic circuit; a blank holder adapted to clamp a blank against one of the dies; a cushioning cylinder; hydraulically actuated means mounted for reciprocation in said cushioning cylinder and connected to said blank holder for resisting movement of said holder during the drawing stroke; hydraulic connections between the pressing cylinder and the cushioning cylinder for maintaining proportionate pressures therein; means operatively connected in the circuit and responsive to the fluid pressure therein for reversing the direction of fluid travel upon the building up in the circuit of a predetermined pressure; means actuated by the movable support and operable at the end of the return stroke for reversing the direction of fluid travel; and means responsive to the fluid pressure in the circuit for decreasing the speed of travel of the movable support when said support approaches the limit of its drawing stroke.
13. In a drawing press, including a press frame, the combination with a pair of die supports mounted on the frame, one of said supports being movable towards and away from the other; of hydraulic actuating means for effecting alternate drawing and return strokes of said movable support, said actuating means including a main pressing cylinder; a die fixed to each support; a source of fluid pressure; means forming with the pressing cylinder and with said source of fluid pressure a hydraulic circuit; a blank holder adapted to clamp a blank against one of the dies; a cushioning cylinder; hydraulically actuated means mounted for reciprocation in said cushioning cylinder and connected to said blank holder for resisting movement of said holder during the drawing stroke; hydraulic connections between the pressing cylinder and the cushioning cylinder for maintaining proportionate pressures therein; a blank holder returning cylinder; hydraulically actuated means mounted for reciprocation in said blank holder returning cylinder and connected to the blank holder for returning the latter to its normal position during the return stroke of the movable support; hydraulic connections between the die returning cylinder and the blank holder returning cylinder; and circuit controlling means operatively connected in the circuit for reversing the direction of fluid travel to alternately direct fluid under pressure into the pressing cylinder and then into the die returning cylinder.
14. In a drawing press, including a press frame, the combination with a pair of die supports mounted on the frame; one of said supports being movable towards and away from the other; of hydraulic actuating means for effecting alternate drawing and return strokes of said movable support, said actuating means including a main pressing cylinder, a die fixed to each support; a source of fluid pressure; means forming with the pressing cylinder and with said source of fluid pressure a hydraulic circuit; a blank holder adapted to clamp a blank against one of the dies; a cushioning cylinder; hydraulically actuated means mounted for reciprocation in said cushioning cylinder and connected to said blank holder for resisting movement of said holder during the drawing stroke; hydraulic connections between the pressing cylinder and the cushioning cylinder for maintaining proportionate pressures therein; circuit controlling means operatively connected with the circuit for reversing the direction of fluid travel to reciprocate the movable support; means responsive to the fluid pressure in the circuit for decreasing the speed of travel of the movable support when said support approaches the limit of its drawing stroke; and means actuated by the movable support for decreasing the speed of travel of said support when the latter approaches the limit of its return stroke.
15. In a drawing press including a press frame, the combination with a pair of die supports mounted on the frame; one of said supports being movable towards and away from the other; of hydraulic actuating means for effecting alternate drawing and return strokes of said movable support, said actuating means including a main pressing cylinder and a die returning cylinder; a die fixed to each support; a source of fluid pressure; means forming with the pressing cylinder and with said source of fluid pressure a hydraulic circuit; a blank holder normally occupying a position at rest and being adapted to clamp a blank against one of the dies; a cushioning cylinder; hydraulically actuated means mounted for reciprocation in said cushioning cylinder and connected to said blank holder for resisting movement of said holder during the drawing stroke; hydraulic connections between the pressing cylinder and the cushioning cylinder for maintaining proportionate pressures therein; a blank holder returning cylinder; hydraulically actuated means mounted for reciprocation in said blank holder returning cylinder and connected to the blank holder for returning the latter to its normal position during the return stroke of the movable support; hydraulic connections between the die returning cylinder and the blank holder returning cylinder; and circuit controlling means operatively connected in the circuit for reversing the direction of fluid travel to alternately direct fluid under pressure into the pressing cylinder and then into the die returning cylinder.
16. In a drawing press including a press frame, a combination with a pair of die supports mount-

ed on the frame, one of said supports being movable towards and away from the other; of hydraulic actuating means for effecting alternate drawing and return strokes of said movable sup-

5 port, said actuating means including a main
pressing cylinder and a die returning cylinder; a
die fixed to each support; a source of fluid pres-
sure; means forming with the pressing cylinder
and with said source of fluid pressure a hydraulic
10 circuit; a blank holder normally occupying a posi-
tion at rest and being adapted to clamp a blank
against one of the dies; a cushioning cylinder;
hydraulically actuated means mounted for recip-
rocation in said cushioning cylinder and con-
15 nected to said blank holder for resisting move-
ment of said holder during the drawing stroke;
hydraulic connections between the pressing cyl-
inder and the cushioning cylinder for maintain-
ing proportionate pressures therein; a blank
20 holder returning cylinder; hydraulically actuated
means mounted for reciprocation in said blank
holder returning cylinder and connected to the
blank holder for returning the latter to its normal
position during the return stroke of the movable
25 support; hydraulic connections between the die
returning cylinder and the blank holder return-
ing cylinder; and circuit controlling means oper-
atively connected in the circuit for reversing the
direction of fluid travel to alternately direct fluid
30 under pressure into the pressing cylinder and
then into the die returning cylinder, said circuit
controlling means including means responsive to
the fluid pressure in the pressing cylinder for re-
versing the direction of fluid travel upon attain-
35 ment of a predetermined pressure in the press-
ing cylinder while the drawing stroke of said die
is being performed.

17. In a drawing press including a press frame, the combination with a pair of die supports 40 mounted on the frame, one of said supports being movable towards and away from the other; of hydraulic actuating means for effecting alternate drawing and return strokes of said movable support, said actuating means including a main 45 pressing cylinder and a die returning cylinder; a die fixed to each support; a source of fluid pressure; means forming with the pressing cylinder and with said source of fluid pressure a hydraulic circuit; a blank holder normally occupying a position 50 at rest and being adapted to clamp a blank against one of the dies; a cushioning cylinder; hydraulically actuated means mounted for reciprocation in said cushioning cylinder and connected to said blank holder for resisting movement of 55 said holder during the drawing stroke; hydraulic connections between the pressing cylinder and the cushioning cylinder for maintaining proportionate pressures therein; a blank holder returning cylinder; hydraulically actuated means 60 mounted for reciprocation in said blank holder returning cylinder and connected to the blank holder for returning the latter to its normal position during the return stroke of the movable support; hydraulic connections between the die 65 returning cylinder and the blank holder returning cylinder; circuit controlling means operatively connected in the circuit for reversing the direction of fluid travel to alternately direct fluid under pressure into the pressing cylinder and 70 then into the die returning cylinder, said circuit controlling means including means responsive to the fluid pressure in the pressing cylinder for reversing the direction of fluid travel upon attainment of a predetermined pressure in the pressing cylinder while the drawing stroke of said die is

being performed; and means actuated by the movable support and operable when the support approaches the end of the return stroke for reversing the direction of fluid travel.

18. In a drawing press including a press frame, 5
the combination with a pair of die supports
mounted on the frame, one of said supports being
movable towards and away from the other; of hy-
draulic actuating means for effecting alternate
drawing and return strokes of said movable sup- 10
port, said actuating means including a main
pressing cylinder and a die returning cylinder; a
die fixed to each support; a source of fluid pres-
sure; means forming with the pressing cylinder
and with said source of fluid pressure a hydraulic 15
circuit; a blank holder normally occupying a posi-
tion at rest and being adapted to clamp a blank
against one of the dies; a cushioning cylinder;
hydraulically actuated means mounted for recip- 20
rocation in said cushioning cylinder and connect-
ed to said blank holder for resisting movement of
said holder during the drawing stroke; hydraulic
connections between the pressing cylinder and
the cushioning cylinder for maintaining propor- 25
tional pressures therein; a blank holder return-
ing cylinder; hydraulically actuated means
mounted for reciprocation in said blank holder
returning cylinder and connected to the blank
holder for returning the latter to its normal posi- 30
tion during the return stroke of the movable
support; hydraulic connections between the die
returning cylinder and the blank holder return-
ing cylinder; circuit controlling means operatively
connected in the circuit for reversing the direction 35
of fluid travel to alternately direct fluid under
pressure into the pressing cylinder and then into
the die returning cylinder, and means responsive
to the fluid pressure in the pressing cylinder
and operable upon attainment of a predetermined 40
pressure therein for reducing the rate of flow
of fluid into the pressing cylinder when the
movable support approaches the end of its draw-
ing stroke.

19. In a drawing press including a press frame, the combination with a pair of die supports mounted on the frame, one of said supports being movable towards and away from the other; of hydraulic actuating means for effecting alternate drawing and return strokes of said movable support, said actuating means including a main pressing cylinder and a die returning cylinder; a die fixed to each support; a source of fluid pressure; means forming with the pressing cylinder and with said source of fluid pressure a hydraulic circuit; a blank holder normally occupying a position at rest and being adapted to clamp a blank against one of the dies; a cushioning cylinder; hydraulically actuated means mounted for reciprocation in said cushioning cylinder and connected to said blank holder for resisting movement of said holder during the drawing stroke; hydraulic connections between the pressing cylinder and the cushioning cylinder for maintaining proportionate pressures therein; a blank holder returning cylinder; hydraulically actuated means mounted for reciprocation in said blank holder returning cylinder and connected to the blank holder for returning the latter to its normal position during the return stroke of the movable support; hydraulic connections between the die returning cylinder and the blank holder returning cylinder; circuit controlling means operatively connected in the circuit for reversing the direction of fluid travel to alternately direct fluid under pressure into the pressing cylinder and then into the die 45

returning cylinder; and means actuated by the movable support for decreasing the rate of flow of fluid into the die returning cylinder when the movable support approaches the end of its return stroke.

20. In a drawing press, the combination with a main ram; of a cooperating main cylinder; a blank holder mounted for movements in opposition to said ram to engage and hold a blank; a blank holder cushioning cylinder; a ram connected to said blank holder and mounted for reciprocatory movements in said cushioning cylinder; and a direct hydraulic connection between said main and cushioning cylinders for maintaining at a constant ratio the hydraulic pressures therein.

21. In a drawing press including a movable die and a movable blank holder; the combination with a main cylinder; of a ram mounted therein for reciprocatory movements and being connected to said movable die; a cushioning cylinder, a ram mounted therein for reciprocatory movements and being connected to said blank holder for yieldably urging the latter towards said mov-

able die to engage and hold a blank; means for supplying fluid under pressure to said main cylinder; and a hydraulic connection between the cushioning cylinder and the main cylinder for maintaining at a constant ratio the hydraulic pressures therein.

22. A method for shaping metal blanks which consists in drawing the blank to be shaped between cooperating dies, one of which is movable and the other stationary, moving the movable die by hydraulic means, clamping a portion of the blank against only the movable die by hydraulic means, and maintaining a free and direct interflow of pressure fluid between the hydraulic drawing means and the hydraulic clamping means, whereby to transmit pressure therebetween in substantially undiminished condition, said interflow of pressure fluid serving to clamp said blank during the drawing operation by a pressure which bears a constant ratio to the drawing pressure.

WALTER ERNST.
